UNITED STATES PATENT OFFICE.

THOMAS W. MCNEILL, OF CHICAGO, ILLINOIS, ASSIGNOR TO REID, MURDOCH & CO., OF CHICAGO, ILLINOIS, A CORPORATION OF ILLINOIS.

ART OF TRANSPORTING MATERIALS IN BULK.

1,181,677.

Specification of Letters Patent.

Patented May 2, 1916.

Original application filed October 21, 1912, Serial No. 726,958. Divided and this application filed September 8, 1913. Serial No. 788,533.

To all whom it may concern:

Be it known that I, THOMAS W. MCNEILL, a citizen of the United States, residing at Chicago, in the county of Cook and State of Illinois, have invented certain new and useful Improvements in the Art of Transporting Materials in Bulk, of which the following is a specification.

My invention relates to new and useful improvements in the art of transporting delicate, easily damaged articles of food stuffs, such as pickles, sauer kraut and the like, in a protecting liquid such as water, brine or the like, from the point of deposit 10 to a desirable point of delivery.

In my copending application, filed October 21, 1912 Serial No. 726,958 I have disclosed a system consisting of certain associated inter-dependent conduits, apparatus, 20 and other appurtenances by which my present method may be carried into effect. In the said application the claims are limited to the physical structure or equivalent, there- 25 in disclosed. This application is a division therefrom.

My present method contemplates the use of a protecting fluid, as a vehicle, within which the articles to be transported or conveyed are submerged and by which they are 30 floated, through the necessary conduits or conductors and devices from the point of deposit to a desirable point of delivery and a subsequent separation of the transported articles from the accompanying protecting 35 liquid, and the reclamation of the liquid.

It further contemplates subjecting, the more or less solid articles, and the liquid within which they are contained, to atmospheric pressure and rarefying the atmospheric conditions of the conduits beyond the point of delivery, then segregating a charge of such conveyed solids and liquids by shutting off communication with the means of rarefaction and the source of supply, and by the effect of gravity, due to the weight of said charge, subjecting the charge to atmospheric pressure thereby to deposit it at the point of delivery.

In manufactories such as required by manufacturing purveyors, it has heretofore 50 been a vexatious problem to convey certain fruits and vegetables, many times partially cooked and therefore soft, from point to point in and around such factory without materially injuring such products. 55

The materials that are especially subject to injury by frequent handling, are sauer kraut, soft pickles, ripe fruit, such as peaches, apples and the like, olives, green peppers, prunes and such other delicate 60 materials or foods that may be conveniently submerged in water or other like liquids without permanent injury. All of which may be conveyed from point to point without material injury by the practice of my 65 method of transportation and at a price per ton incomparably cheap when considered with respect to the usual methods heretofore employed.

In an example of the practice of my invention, cucumber pickles were submerged in 50 per cent. liquid, such as brine. The tank or trap was sufficiently large to contain 750 pounds of pickles and brine at a charge when two-thirds full; the point of 75 deposit was 200 feet removed from the point of delivery. The apparatus, worked automatically and delivered pickles and brine at the point of delivery at the rate of one ton per minute. The performance, when conveying other materials has been equally 80 satisfactory. The articles were not damaged to any noticeable extent. Apparatus having larger or smaller capacities may be made and used with equal facility. 85

If the articles mentioned were conveyed in a dry system without the introduction of water, as the vehicle, contact of the moving articles with the solid walls and other portions of the conveying system would 90 bruise the articles and otherwise disfigure, soil and injure them, so as to render such a system poorly adapted for this purpose.

In the accompanying drawings forming a part hereof:—Figure 1 is an elevation, 95 partly in section of an apparatus by which

my system may be carried into effect. Fig. 2 is an enlarged elevation, partly in section, of a segregating trap in which a charge of material transported is segregated and from which it is finally deposited by the effect of gravity. Fig. 3 is an enlarged sectional view of the air controlling valve, by means of which the trap is disconnected from the air system and the contents subjected to atmospheric pressure. Fig. 4 is an enlarged detailed sectional view of a retarding device that prevents spasmodic movement of the segregating trap, or receptacle.

In all the views the same reference characters are employed to indicate similar parts.

5 is a tank or other depository containing materials to be conveyed by my system. Said materials 6 are shown to be submerged in a liquid 7. The contents of the depository 5 is to be conveyed therefrom to conveyer 8 or other point of deposit, by the instrumentality of the intervening means to which my system is adapted. A pipe 9 serves as a conduit through which the material and the liquid are to pass. It is provided with a plurality of fittings, such as 10, which are normally closed by caps 11 and to which a hose 12 may be connected at any suitable point. It is also provided 25 with a plurality of fittings 13 having caps 14, that are normally closed, to which a hose 15 may be connected at suitable points along the conduit or pipe 9. The free end of the hose 12 passes into the tank or depository 15. An air exhaust pump 16 is employed to produce rarefaction in the tank 17 and the pipe 18 which is connected thereto. The pipe 18 is provided with a series of valves 19 which are distributed along its 30 length and with the mouths normally closed, and to which a hose 20 may be connected. The fittings 13 of the pipe 9 and the fittings 19 of the pipe 18 should be located in pairs for convenient connection of the hose 15 and 20 of the trap 21, as shown in Fig. 1. The hose 12 may be connected to the pipe 9 at any convenient point adjacent the tank or depository 5. The tank or trap 21 is shown in cross sections in Fig. 2 and consists of 35 a main body part open at its bottom, as at 22, and provided with a valve 23 that is counterbalanced by an adjustable weight 24 so that it normally holds the valve 23 closed, as shown in full lines in Fig. 2. The hose 15 is connected to the fitting 25 which is provided on its inner end with an automatically closing valve 26 pivoted, as at 27. Near the center of the head 28 is a projecting arm 29, connected to a transversely positioned lever 30, as at 31, said lever being supported by and pivotally connected to a vertically depending arm 32, as at 33. The lever 30 bears an adjustable counterweight

34, which normally holds the tank, or trap 21, in elevated position, as shown in full lines in Fig. 2. When the trap becomes filled with the articles to be transported the weight of the articles together with that of the trap will overcome the weight of the counterweight 34 and raise it to the dotted line position shown in Fig. 2. A pipe 35 is connected to the hose 20 for connection with the tank 17. An air valve 36, in the pipe 20, is adapted for oscillation by means of an arm 37. The arm 37 is connected to 75 the pivoted lever 30 by means of a link 38 so that when the parts are in the position shown in full lines in Fig. 2 the valve controlling communication with the tank 17 will be open causing communication between 80 said tank 17 and interior of the trap 21, as more clearly shown in Fig. 3. Now when the parts assume the positions shown in dotted lines in Fig. 2 the valve 36 will be closed and communication will be established between the interior of the trap 21 and the exterior atmosphere through the pipe 39. When the parts are in dotted line position a latch 40, pivoted as at 41 to the body part 85 of the trap, serves to engage a latch member 42, which moves with the valve 23 and holds the valve open, but when the tank or trap 21 is emptied of its contents the weight 34 will overcome it and lift it to full line position, at which time the latch 40 will be 90 raised and the counter weight 24 will close the valve 23 and at this time the interior of the trap 21 is again connected with the tank 17, and the air, will be drawn from the trap 21 and the atmospheric pressure 95 from the outside, due to the attenuation on the inside, will serve to hold the valve 23 tightly closed.

The operation of the system in carrying my method of transportation into effect, is as 105 follows:—The pump 16 is set in operation and the tank 17 is substantially exhausted of air, or as nearly as may be, and the connecting pipe 18 with the hose 20, the trap 21, hose 15, pipe 9 and hose 12 are all exhausted of air, the attenuation extending to the bottom of the hose 12, which at this time is submerged in the depository 5 containing the articles to be transported. The outside atmospheric pressure, to which the 110 contents of the tank or depository 5 is subjected, will force the liquid and the contained articles into the pipe 12, through the fitting 10 into the pipe 9 and hose 15 and finally into the trap or tank 21 until the 115 tank 21 becomes practically two-thirds full at which time the weight of the tank, and its contents, will overcome the counterbalancing weight 34 lifting the counterbalance weight to dotted line position and causing 120 the tank to be depressed to the dotted line

position at which time the valve 36 is turned so as to shut off the air exhaust means and to open communication between the interior of the trap 21 and the outside atmosphere thus 5 breaking the vacuum tendency in the tank. After this has been accomplished there is no longer a force holding the valve 23 closed and the weight of the contents causes it to open and assume substantially the position 10 shown in dotted lines in Fig. 2 at which time the latch member, 42, is brought into engagement with the pivoted latch bar 40 and the valve is held open by the instrumentality of an adjustable rod 43 having a 15 slot and pin connection 44 with the lever 37. The valve 23 will be held by the latch in this position until the tank again is raised by the overbalancing weight 34, to full line position, at which time the arm 37 will be 20 moved, the rod 43 raised and the latch 40 lifted, to the position shown, thus releasing the valve 23 and permitting the counter-weight 24 to close the valve. At the same time that the tank is being emptied the atmospheric pressure will automatically close 25 the valve 26 thereby preventing air from entering the hose 15, pipe 9, fitting 10 and hose 12, and retaining the contents within these parts and preventing them from re- 30 turning to the tank from whence they came which otherwise they would do by siphoning action.

When the articles transported are discharged from the trap 21 they fall upon an 35 inclined screen 45, the screen being perforated to permit the liquid in which they are transported to be separated from the article. The liquid passes through the screen into a receiver, 46 and from thence 40 by means of a pipe 47 it is returned to the point or depository from which it came, or, if desired, the valve 48 may be closed and the valve 49 opened when the liquid will be discharged from the receiver 46 to the sewer 45 by means of pipe 50. Where the liquid is 50 of any value, such as brine, or the like, I prefer to return it by gravity to the tank or receiver 5 or by pump to the place from which it was taken, so that it may be used over again. The articles transported after falling on the inclined perforate apron 45 are deposited upon a traveling conveyer 8 by which they may be conveyed to any convenient locality without the use of the protecting liquid, or they may be caused to fall 55 into proper receptacles such as barrels or other receptacles after leaving the inclined apron 45, as desired.

Having described my invention, what I 60 claim with a view and desire to secure by Letters Patent is:—

1. The art of conveying small, solid articles, such as pickles, sauer-kraut, and the

like, from a point of supply to a delivery chamber, which consists in, submerging the 65 solids in a protecting liquid, the surface of which is exposed to atmospheric pressure, establishing an area of rarefaction, and alternately, first, closing the delivery chamber to the atmosphere and establishing communication thereto from the area of rarefaction, establishing communication with the supply beneath the surface of the liquid, and second, shutting off communication between the delivery chamber and the area of 75 rarefaction and opening the delivery chamber to the atmosphere for contents delivery.

2. The art of conveying small, solid articles, such as pickles, sauer-kraut, and the 80 like, by conveying the same from a point of supply to a delivery chamber, which consists in submerging the solids in a protecting liquid, the surface of which is exposed to atmospheric pressure, establishing an 85 area of rarefaction, and alternately, first, closing the delivery chamber to the atmosphere and establishing communication thereto from the area of rarefaction, establishing communication with the supply, beneath the surface of the liquid, and second, shutting off the communication between the delivery chamber and the area of rarefaction, closing the chamber from connection with the source of supply, and opening it 90 to the atmosphere for contents delivery.

3. The art of conveying small, solid articles, such as pickles, sauer-kraut, and the like, from a point of supply to a delivery chamber which consists in, submerging the 100 solids in a protecting liquid, the surface of which is exposed to atmospheric pressure, establishing an area of rarefaction and alternately, first, closing the delivery chamber to the atmosphere and establishing communication thereto from the area of rarefaction, and to the source of supply beneath the surface of the liquid, and second, shutting off communication between the delivery chamber and the area of rarefaction and 105 opening it to the atmosphere, and discharging the contents of the chamber upon a separating area and there permitting the liquid to separate from the solid by gravity.

4. The method of operating an installation for conveying small articles of food stuffs, such as pickles, sauer-kraut, etc., submerged in a protecting liquid that comprises a supply tank containing the liquid and food stuffs, a delivery receptacle having 115 an outwardly opening bottom delivery gate, a material conveying pipe connecting the submerged portion of the tank with the delivery receptacle, and a suction device connected with the top part of said delivery 120 receptacle;—which consists in, controlling

the intake and delivery operation of the delivery receptacle by alternately first connecting the closed receptacle with the suction device and closing it to the atmosphere, 5 and second, closing it to the suction device, establishing communication between the closed receptacle and the atmosphere, the bottom gate being closed against load depressions while rarefaction exists in the re-

ceptacle and permitting the gate to be load 10 opened when rarefaction is diminished.

In testimony whereof I hereunto set my hand in the presence of two witnesses.

THOMAS W. McNEILL.

In the presence of—

FORÉE BAIN,

MARY F. ALLEN.
